UNITED STATES PATENT OFFICE

110,577

DESIGN FOR AN AMUSEMENT TOWER

Joseph B. Strauss, San Francisco, Calif.

Application February 1, 1938, Serial No. 74,773

Term of patent 3½ years

To all whom it may concern:

Be it known that I, Joseph B. Strauss, a citizen of the United States of America, residing at San Francisco, in the county of San Francisco and State of California, have invented a new, original, and ornamental Design for an Amusement Tower, of which the following is a specification, reference being had to the accompanying drawing, forming a part thereof.

The figure is a side elevation of an amusement tower, showing my new design, all sides having the same appearance.

I claim:

The ornamental design for an amusement tower, substantially as shown and described.

JOSEPH B. STRAUSS.
